URINARY METERING CONTAINER OR SIMILAR ARTICLE

William L. Smith, Warwick, R.I., assignor to Davol Rubber Company, Providence, R.I., a corporation of Rhode Island

Filed Apr. 20, 1964, Ser. No. 79,607

Term of patent 14 years

(Cl. D83—1)

FIG. 1 is a perspective view of a urinary metering container or similar article showing my new design;

FIG. 2 is an enlarged side elevational view thereof, it being understood that my container has the same appearance from both sides;

FIG. 3 is an enlarged top plane view thereof; and

FIG. 4 is an enlarged bottom view thereof.

The hanger support disclosed in FIG. 1 is broken away for convenience of illustration, and the tube member disclosed in FIGS. 1, 2 and 3 is broken away to indicate indeterminate length.

I claim:

The ornamental design for a urinary metering container or similar article, substantially as shown and described.
